UNITED STATES PATENT OFFICE.

HARRY WARD LEONARD, OF NEW YORK, N. Y.

RESISTANCE-BOX.

SPECIFICATION forming part of Letters Patent No. 635,441, dated October 24, 1899.

Application filed November 3, 1898. Serial No. 695,370. (No model.)

To all whom it may concern:

Be it known that I, HARRY WARD LEONARD, a citizen of the United States, residing in the borough of Manhattan, city of New York, county and State of New York, have invented 5 a certain new and useful Improvement in Resistance-Boxes, of which the following is a specification.

My invention relates to improvements in 10 resistance-boxes and similar apparatus, and especially to resistance-boxes employed for starting and accelerating electric motors.

The object of my invention is to make the apparatus as a whole more compact, simpler 15 and cheaper to manufacture than heretofore, more durable and better adapted to the uses for which the apparatus is designed, and to enable the apparatus when damaged to be more readily and more cheaply repaired than 20 was heretofore possible.

In carrying my invention into effect I prefer to employ a resistance made in the form of a ribbon and preferably reflexed or otherwise bent into shape, so that a considerable 25 length of resistance may be disposed in a comparatively small space. For the resistance material I preferably employ a metal or alloy having a high fusing-point and low-temperature coefficient for change of resistance by 30 change of temperature. This resistance I arrange within a shallow metal box, preferably cast-iron, and which is covered on the inner side with a layer of insulation, either by providing the same with a layer of asbestos 35 or equivalent heat-resisting insulating material or by coating the same with an insulating compound capable of withstanding a high heat; but I prefer to apply a layer of porcelain enamel. When the resistance is 40 placed in position within the box and connected with the usual binding-posts, I fill the box with sand or equivalent material, preferably sand. This sand is preferably a pure grade of sand, such as Berkshire sand, having 45 a high capacity for heat absorption and possessing high insulating properties and one which is not readily affected by moisture or heat. The sand being quite fine it readily fills all spaces within the box between and 50 around the sections of the resistance and attached parts, and thus effectively insulates all parts of the apparatus located within the

box. The box is closed by a metal lid having its inner side covered with insulation in the same manner as the box, and before placing the lid in position its edges or the edges of the box receive a layer of sealing material—such, for instance, as putty—so that when the cover is secured in position, either by screws or otherwise, the box is well sealed, 55 thus preventing the entrance of moisture and preventing the sand from working out. Since the resistance is secured only to the terminals or binding-posts for the steps or sections of the resistance, it will be seen that the loops 60 between such binding-posts embedded in the sand or equivalent material will be entirely free to expand and contract with the changes in temperature without producing any injurious strains, as is the case in the constructions 65 70 in which the resistance is secured directly to its support. Another advantage is that in completing the resistance-box the parts are not subjected to heat, as in the constructions just mentioned. It will thus be seen that the 75 cost of manufacture of the apparatus thus outlined is very low, that the parts are readily and quickly placed in position, and that the apparatus may be readily taken apart for alteration or repair. Furthermore, the apparatus is very strong and compact, and the cast-iron box filled with sand has a very high 80 capacity for absorbing heat energy because of the high specific capacity of the iron and sand for heat. The porcelain-enamel lining 85 gives an insulation on the surface of the iron which is extremely perfect and not affected by heat, moisture, or any conditions met with in practice, and such a coating can be readily made to withstand a pressure of many thou- 90 sand volts alternating electromotive force without injuring its insulating quality. The sand insulation between and around the parts located in the box is not readily affected by heat even though the temperature of the con- 95 ductor reaches the melting-point.

It will be readily seen that should the apparatus become damaged—such, for instance, as the burning out of the resistance—the apparatus may be readily repaired by first removing the cover and then removing the sand insulation and the burned-out resistance. When a new step of resistance is put in position in place of the burned-out step, the 100

box is again filled with sand and the cover replaced, when the apparatus will be practically as good as when originally constructed, and practically the entire cost of repair in such a case would be represented by the cost of a new step of resistance, the cost of which is extremely low, being only a few cents.

I am aware that it has been heretofore proposed to construct resistance-boxes wherein the resistance was embedded in sand; but so far as I am aware no one prior to my invention has produced a practical resistance-box of the character described. The box itself should be moisture-proof as far as practicable to prevent the sand from absorbing moisture, and I have found by experiment that the metal box must be lined with insulation not only to guard against a short circuit between the box and resistance due to moisture, but to guard against accidental contact between the box and resistance. I have also found that if any water be present in the box, either combined, as in cement, or otherwise, the heating of the conductor and sand when the resistance-box is in use will cause the moisture to collect on the inner side of the metal box, and unless the layer of insulation were provided on the inner side of the box a ground would soon be formed between it and the resistance.

I have found in practice that as a starting resistance for a twenty-five-horse-power motor a resistance-box constructed in accordance with my invention and provided with a resistance of the proper capacity the size of the box need not be over fourteen by fourteen by one and one-half inches. For such motors resistance-boxes as heretofore constructed and in which the resistance was composed of coils of galvanized or tinned ironware were many times larger than the size above stated and very expensive and the resistance could not be so well protected as with my improved apparatus.

In making resistances for large motors—such, for example, as three-hundred-horse power—I prefer to employ a series of resistance-boxes of about the size stated, the boxes, or rather the resistances of each box, being arranged in multiple with relation to each other. Such boxes would be secured together so as to form a bank of resistances, connections of course being made with a suitable controller. By this means a standard form of resistance-box may be employed for motors operating on circuits of given voltages—that is to say, one standard box would be for a twenty-five-horse-power motor employed on one-hundred-and-twenty-five-volt circuits, another standard box for a twenty-five-horse-power motor operating on two-hundred-and-fifty-volt circuits, and a third standard box for a twenty-five-horse-power motor operating on five-hundred-volt circuits, and by grouping resistance-boxes of the same standard in banks resistances may be readily made up for motors varying from twenty-five-horse

power up and operating on circuits of one hundred and twenty-five, two hundred and fifty, or five hundred volts. Thus it will be seen that only three types of resistance-boxes would be necessary for all customary uses, and each of the three types would be alike in all respects, except as regards the capacity of the resistance-ribbon. Thus it will be seen that the manufacture of resistance-boxes may be very much simplified by means of my invention and the cost materially reduced on that account. The boxes will be of uniform size, but for the three types of motors mentioned the resistances will vary. With boxes and resistances in stock resistance-boxes of any capacity can be made up in a very short time by means of my invention. All that is necessary is to select the necessary number of resistances of proper capacity, place them in the boxes, fill the boxes with sand, and apply the covers.

My invention is illustrated in the accompanying drawings, in which—

Figure 1 is a plan view of the preferred form of my improved resistance-box, the lid being removed. Fig. 2 is a cross-section, and Fig. 3 an elevation illustrating a bank of resistance-boxes.

Referring to the drawings, A is the cast-iron box, which may be made in any desired form and is provided with a lid or cover B, adapted to be secured to the box by any suitable means. The box and lid are respectively provided with ribs a and b for increasing the heat-radiating surface. The inner sides of the box and lid are covered with a layer of insulating material C capable of withstanding high heat, which, as before stated, may be asbestos or other insulating material, or the insulation may be an insulating compound applied in a liquid or semi-liquid form, but it is preferably a coating of porcelain enamel. The resistance-box is provided with a series of binding-posts D, projecting through one side of the box or through the bottom (both ways being shown) and preferably insulated by bushings d and washers d', of any suitable insulating material. These binding-posts are held in position by nuts d², and at the outer ends are provided nuts d³ for securing the circuit-terminals. The sections of the resistance E are secured to clamps e, which in turn are secured to the binding-posts between the washer d' and a metal washer d⁴. As before stated, the resistance is in the form of a thin ribbon, and this ribbon is preferably reflexed, as shown, and placed edgewise in the box. As a precautionary measure a strip of insulating material F may be placed edgewise between the adjacent sections of the resistance, as shown in dotted lines, although in practice I have found that it is not absolutely necessary. When the resistance E is placed in position and the sections secured to the binding-posts D, as described, the box is filled with a fine sand G. Before placing the cover in position

I apply to the edge of the box or cover a layer of sealing material b' —such, for instance, as putty, although any suitable material may be employed—and the cover is then firmly secured in position by screws passing through the cover into the sides of the box or otherwise. To improve the joint between the box and cover, I provide the edge of the box with a groove a' to retain the sealing material.

5 10 Each box is also provided with four legs or studs A' , one at each corner of the box, and through each leg or stud is formed a hole A^2 to receive a screw for securing the box in position. The studs A' and holes A^2 are also 15 designed for use in arranging the resistance-boxes in banks, as shown in Fig. 3; the studs, with additional pieces of tubing, serving as spacing-blocks, and through the holes A^2 are passed rods by means of which the several 20 boxes are clamped together and secured to a suitable base or supporting-stand.

What I claim is—

1. In a resistance-box, the combination of a metal box, a resistance in the box, a finely-divided mineral insulating filling material in 25 said box, and a cover for said box having sealed joints.

2. In a resistance-box, the combination of a metal box, an insulating-lining for such box, 30 a resistance in the box, a finely-divided mineral insulating filling material in said box, and a cover for said box having sealed joints.

3. In a resistance-box, the combination of a metal box, a heat-resisting insulating-lining 35 for such box, a resistance in the box, a finely-divided mineral insulating filling material in said box, and a cover for said box having sealed joints.

4. In a resistance-box, the combination of 40 a metal box, a porcelain-enamel insulating-lining for such box, a resistance in the box, a finely-divided mineral insulating filling material in said box, and a cover for said box having sealed joints.

45 5. In a resistance-box, the combination of a metal box, an insulating-lining for such box, a reflexed resistance in the box, insulating-partitions between adjacent sections of the resistance, and a mineral insulating filling 50 material in said box.

6. In a resistance-box, the combination of a metal box, a heat-resisting insulating-lining for such box, a reflexed resistance in the box, insulating-partitions between adjacent sections of the resistance, a finely-divided mineral insulating filling material in said box, and a cover for said box having sealed joints.

55 7. In a resistance-box, the combination of a metal box, a porcelain-enamel insulating-lining for such box, a reflexed resistance in the box, insulating-partitions between adjacent sections of the resistance, a finely-divided mineral insulating filling material in said box, and a cover for said box having sealed joints.

65 8. In a resistance-box, the combination of a metal box, a porcelain-enamel insulating-lining for such box, a resistance in the form

of a tape or ribbon in the box, and a mineral insulating filling material in said box.

9. In a resistance-box, the combination of 70 a metal box, an insulating-lining for such box, a resistance in the form of a tape or ribbon in the box, a finely-divided mineral insulating filling material in said box, and a cover for said box having sealed joints.

10. In a resistance-box, the combination of a metal box, a heat-resisting insulating-lining for such box, a resistance in the form of a tape or ribbon in the box, a finely-divided 80 mineral insulating filling material in said box, and a cover for said box having sealed joints.

11. In a resistance-box, the combination of a metal box, a porcelain-enamel insulating-lining for such box, a resistance in the form of a tape or ribbon in the box, a finely-divided 85 mineral insulating filling material in said box, and a cover for said box having sealed joints.

12. In a resistance-box, the combination of a metal box, a heat-resisting insulating-lining for such box, a reflexed resistance in the 90 form of a tape or ribbon in the box, insulating-partitions between adjacent sections of the resistance, a finely-divided mineral insulating filling material in said box, and a cover for said box having sealed joints.

13. In a resistance-box, the combination of a metal box, a resistance in the box, said resistance being arranged in steps connected with a series of insulated contacts or binding-posts, a finely-divided mineral insulating filling 100 material in said box for insulating adjacent sections of the resistance from each other and for absorbing and conducting the heat from said resistance to the metal box, and a cover for said box having sealed joints. 105

14. In a resistance-box, the combination of a metal box, an insulating-lining for such box, a resistance in the box, said resistance being arranged in steps connected with a series of insulated contacts or binding-posts, a finely-divided mineral insulating filling material in 110 said box for insulating adjacent sections of the resistance from each other and for absorbing and conducting the heat from said resistance to the metal box, and a cover for 115 said box having sealed joints.

15. In a resistance-box, the combination of a metal box, a resistance in the box, said resistance being arranged in steps connected with a series of insulated contacts or binding-posts, said resistance being unattached to said box except where connected to said contacts or binding-posts, a finely-divided mineral insulating filling material in said box for insulating adjacent sections of the resistance from 120 each other and for absorbing and conducting the heat from said resistance to the metal box, and a cover for said box having sealed joints.

16. In a resistance-box, the combination of a metal box, an insulating-lining for such box, 125 a resistance in the box, said resistance being arranged in steps connected with a series of insulated contacts or binding-posts, and said resistance being unattached to said box ex-

- cept where connected to said contacts or binding-posts, a finely-divided mineral insulating filling material in said box for insulating adjacent sections of the resistance from each other and for absorbing and conducting the heat from said resistance to the metal box, and a cover for said box having sealed joints.
17. In a resistance-box, the combination of a metal box, a porcelain-enamel insulating-lining for such box, a resistance in the box, said resistance being arranged in steps connected with a series of insulated contacts or binding-posts, and said resistance being unattached to said box except where connected to said contacts or binding-posts, a finely-divided mineral insulating filling material in said box for insulating adjacent sections of the resistance from each other and for absorbing and conducting the heat from said resistance to the metal box, and a cover for said box having sealed joints.
18. In a resistance-box, the combination of a metal box, an insulating-lining for such box, a resistance in the form of a tape or ribbon in the box, said resistance being arranged in steps connected with a series of insulated contacts or binding-posts, and said resistance being unattached to said box except where connected to said contacts or binding-posts, a finely-divided mineral insulating filling material in said box for insulating adjacent sections of the resistance from each other and for absorbing and conducting the heat from said resistance to the metal box, and a cover for said box having sealed joints.
19. In a resistance-box, the combination of a metal box, a porcelain-enamel insulating-lining for such box, a resistance in the form of a tape or ribbon in the box, said resistance being arranged in steps connected with a series of insulated contacts or binding-posts, and said resistance being unattached to said box except where connected to said contacts or binding-posts, a finely-divided mineral insulating filling material in said box for insulating adjacent sections of the resistance from each other and for absorbing and conducting the heat from said resistance to the metal box, and a cover for said box having sealed joints.
20. In a resistance-box, the combination of a shallow box, a resistance within said box arranged in steps or sections, terminals to which said steps or sections are connected, a finely-divided insulating filling material surrounding said resistance, and a removable cover for said box having sealed joints.
21. In a resistance-box, the combination of a shallow metal box, a resistance within said box arranged in steps or sections, terminals to which said steps or sections are connected, a finely-divided insulating filling material surrounding said resistance, and a removable cover for said box having sealed joints.
22. In a resistance-box, the combination of a shallow metal box having an insulating lining, a resistance within said box arranged in steps or sections, terminals to which said steps or sections are connected, a finely-divided insulating filling material surrounding said resistance, and a removable cover for said box having sealed joints.
23. In a resistance-box, the combination of a box having two large parallel surfaces and a relatively narrow edge, one of the large surfaces being in the form of a cover, a resistance within the box arranged in steps or sections, terminals to which said steps or sections are connected, and a removable filling of mineral insulating material surrounding said resistance.
24. In a resistance-box, the combination of a cast-iron box having two large parallel surfaces and a relatively narrow edge, one of the large surfaces being in the form of a cover, a resistance within the box arranged in steps or sections, terminals to which said steps or sections are connected, and a removable filling of mineral insulating material surrounding said resistance.
25. In a resistance-box, the combination of a box having two large parallel surfaces and a relatively narrow edge, one of the large surfaces being in the form of a cover, a resistance in the form of a tape or ribbon placed edgewise in the box and arranged in steps or sections, terminals to which said steps or sections are connected, and a removable filling of mineral insulating material surrounding said resistance.
26. In a resistance-box, the combination of a box having two large parallel surfaces and a relatively narrow edge, one of the large surfaces being in the form of a cover having sealed joints, a resistance in the box and arranged in steps or sections, terminals to which said steps or sections are connected, and a finely-divided insulating filling material surrounding said resistance.
27. In a resistance-box, the combination of a box having two large parallel surfaces and a relatively narrow edge, one of the large surfaces being in the form of a cover having sealed joints, a resistance in the form of a tape or ribbon placed edgewise in the box and arranged in steps or sections, terminals to which said steps or sections are connected, and a finely-divided insulating filling material surrounding said resistance.
28. In a resistance-box, the combination of a cast-iron box having two large parallel surfaces and a relatively narrow edge, one of the large surfaces being in the form of a cover having sealed joints, a lining of insulation, a resistance in the box and arranged in steps or sections, terminals to which said steps or sections are connected, and a finely-divided insulating filling material surrounding said resistance.
